MEASURING SCOOP

William Marcus, Cleveland, Ohio, assignor to
Merrymaid Plastics Corporation

Filed Apr. 1, 1963, Ser. No. 74,232

Term of patent 14 years

(Cl. D44—29)

FIG. 1

FIG. 2

FIG. 3

FIGURE 1 is a perspective view of a measuring scoop showing my new design and looking into the scoop;

FIGURE 2 is a side elevational view; and

FIGURE 3 is a side elevational view with the scoop rotated 90° to the left from its position in FIG. 2.

I claim:

The ornamental design for a measuring scoop, as shown.
